DESIGN FOR A COMBINATION SHAVING SOAP JAR AND ASH TRAY

Samuel P. Benjamin, Jr., West Haven, Conn., assignor to Weldon, Inc., New York, N. Y.

Application October 26, 1944, Serial No. 115,995

Term of patent 7 years

(Cl. D85—2)

To all whom it may concern:

Be it known that I, Samuel P. Benjamin, Jr., a citizen of the United States, residing at West Haven, in the county of New Haven and State of Connecticut, have invented a new, original, and ornamental Design for a Combination Shaving Soap Jar and Ash Tray, of which the following is a specification, reference being had to the accompanying drawing, forming part thereof.

Figure 1 is a top plan view of a combination shaving soap jar and ash tray showing my new design.

I claim:

The ornamental design for a combination shaving soap jar and ash tray, as shown.

SAMUEL P. BENJAMIN, JR.
